METHOD OF AND MEANS FOR FINISHING WALL JOINTS

Application filed March 14, 1929. Serial No. 347,107.

This invention relates to the finishing of wall joints and is especially, though not exclusively, applicable to walls constructed of wall-boards arranged edge to edge.

5 Ordinarily in joints of this character the small space between the ends of the boards is filled with a joint filler of any desired character and frequently a narrow strip or tape of suitable material is then placed over 10 the joint. Such joints, however, break the smoothness of the wall and are visible when the wall is decorated.

The present invention has for its object to provide a method of, and means for, providing a finish for such joints which to all 15 intents and purposes is invisible, and which at the same time seals the joint effectively and conceals the nails which may be used for securing the boards in place.

20 The means provided by the present invention are simple and inexpensive and the method can be carried out rapidly and by relatively unskilled persons.

The invention consists in the method and 25 means hereinafter described and more fully set forth in the appended claims.

Referring now to the accompanying drawings, which illustrate diagrammatically one manner of carrying the invention into effect,

30 Figure 1 is a front elevation,

Figure 2 is a plan view of Figure 1,

Figure 3 is a front elevation illustrating later stages of the process.

35 Figure 4 is a plan view of a completed joint, and

Figure 5 is a view of the adhesive surface of the paper strip used for carrying out the improved process.

40 In Figures 1 to 4, the marginal portions of two wall-boards A and B are shown abutting against each other at 1. As illustrated, the invention is applied to wall-boards of the type comprising a layer 2 of cellular gypsum covered on each side with paper as indicated at 3. It will be understood, however, that the invention is applicable to any other kinds of wall building materials which present joints requiring finishing treatment.

45 According to the invention a strip of suit-

able paper 4 is secured to the marginal portions of the front surfaces of the boards A and B by means of glue or other adhesive, preferably a colourless and transparent adhesive. The paper 4 is stuck to the boards 55 A and B from the points 5 to 6, the outer edge of the paper being left free as indicated at 7 (see Figure 2). The paper 4 is left in the condition indicated in Figures 1 and 2 until the adhesive has completely dried, and 60 then the free edges 7 are torn off. The removal of the free edges 7 is accomplished in such a manner that the paper is divided or split laterally as well as longitudinally. This may be done by grasping the upper end 65 of a free edge 7 and pulling it downwardly and also towards the middle of the strip of paper 4, as indicated roughly by the arrow α in Figure 3. The paper is thus divided laterally from 6 to 8, and very fine, sharp edges 70 are produced at 6 and at the inner edge 6' of the strip of paper which is torn from the strip 4. This tearing action is illustrated diagrammatically at the right-hand side of the strip 4 in Figure 3. The left-hand side 75 of strip 4 in Figure 3 is shown as it appears when the left-hand free portion 7 has been removed. It will thus be seen that, after the tearing operation has been completed, the middle or untorn zone 9 of strip 4, the torn 80 or split zones 10, and the outer surfaces of the wall-boards A and B merge smoothly one into another, and the slight elevation of zone 9 is imperceptible on account of the great width of the zones 10 in relation to the thickness of paper 4 (see Figure 4). The very 85 gradual slope of the zones 10 and the consequent absence of abrupt variations of level, eliminate the production of shadows, and thus render the joint invisible. The joint 90 may be further finished by buffing or smoothing the torn zones 10 with a suitable tool to remove any slight irregularities which may exist along the lines 6 and 8, and the wall 95 may then be decorated. It will be understood that, while distinct lines are shown at 6 and 8 in Figure 3 for the purpose of illustration, such lines are actually practically invisible if the paper 4 is of the same colour as

100 the paper 3.

6 A portion of a convenient strip of paper 4
for use in carrying out the process is shown
in Figure 5. This strip bears a central, lon-
gitudinal band of material, indicated by
stippling at 11, which can be rendered ad-
hesive by moistening. The longitudinal mar-
gins 7, it will be understood, are devoid of
adhesive material.

10 The width, and therefore the slope, of the
torn zones 10 can be varied by varying the
angle at which the pulling force is applied
to remove the marginal portions 7 of the
strip 4.

15 Any suitable tough, and fairly thick, paper
of a character similar to that of stout wrap-
ping paper may be used to form the strip 4.
It is probable that the best results are ob-
tainable by the use of a paper in which the
fibres are oriented in the direction of the
20 length of the strip as indicated on the torn
zones 10 in Figure 3, but this is not essen-
tial.

25 What we claim is:

1. A process of finishing the joints of walls,
which comprises sticking the central, longi-
tudinal portion of a paper strip over the joint
and removing the marginal portions of the
strip in such a manner as to divide or split
the marginal portions of the strip.

30 2. A process of finishing the joint between
a pair of boards arranged edge to edge, which
comprises sticking the central, longitudinal
portion of a paper strip over said joint, leav-
ing the edges of said strip free and applying
35 an obliquely directed pulling force to the free
edges of said strip so that a torn surface is
produced on the adhering portion of the strip,
which torn surface is of a great width in re-
lation to the thickness of the paper strip.

40 3. A process as claimed in claim 2, wherein
the torn surfaces of the paper strip are sub-
jected to a smoothing or buffing treatment.

45 4. A process of forming a wall, which com-
prises arranging boards edge to edge, caus-
ing a strip of flexible fibrous material to ad-
here to the adjoining marginal surfaces of
said boards, and tearing off the edges of said
strip of material so as to produce inclined,
50 torn surfaces at the lateral margins of said
strip, which torn surfaces merge impercepti-
bly into the surfaces of said boards on one
side and the central, longitudinal portion of
said strip on the other.

55 5. An article of manufacture for use in the
finishing of wall joints, consisting of a strip
of paper bearing a longitudinal, central band
of material capable of being rendered adhe-
sive by moistening, the marginal portions of
said strip being devoid of adhesive material.

60 6. An article of manufacture for use in the
finishing of wall joints, consisting of a strip
of stout paper, the fibres of which are oriented
in the direction of length of said strip, the
longitudinal central portion of said strip be-
ing provided on one side with material ca-

pable of being rendered adhesive by moisten-
ing.

In testimony whereof we have affixed our
signatures.

ROBERT E. HAIRE.
GEORGE M. THOMSON.
